UNITED STATES PATENT OFFICE.

MILLARD P. OSBOURN, OF MERCHANTVILLE, NEW JERSEY, ASSIGNOR TO
WARREN WEBSTER AND COMPANY, A CORPORATION OF NEW JERSEY.

APPARATUS FOR CONTROLLING THE DISCHARGE OF DRIPS FROM OIL-SEPARATORS.

SPECIFICATION forming part of Letters Patent No. 767,709, dated August 16, 1904.

Application filed August 6, 1903. Serial No. 168,417. (No model.)

To all whom it may concern:

Be it known that I, MILLARD P. OSBOURN, of Merchantville, Camden county, State of New Jersey, have invented an Improvement in 5 Apparatus for Controlling the Discharge of Drips from Oil-Separators, of which the following is a specification.

In draining the drips from oil-separators, and particularly those placed between the engine and condenser and operating under a partial vacuum, much difficulty has been experienced in preventing the waste of steam under some conditions or a loss of vacuum under other conditions when the drips are dis- 15 charged or drawn off.

It is the object of this invention to enable the discharge of the drips to be automatically controlled by the level of the drips in the separator or drip-chamber, so that proper drainage may take place at all times without requiring any special attention from the engine driver and the escape and waste of steam from the separator or loss of vacuum will be entirely prevented.

25 In the drawing the figure is a side elevation of my improved apparatus for controlling the discharge of drips from an oil-separator operating under vacuum conditions.

30 *a* is an oil-separator, which the steam enters by the inlet *b* and leaves by the outlet *c*. It may be of any suitable construction.

The separator is provided with a drip-chamber *d*, from which the oil and oily water are discharged through a suitable outlet *p*.

35 In systems where a vacuous condition is normally maintained in the separator the contents of the drip-chamber *d* are discharged to a pump *e* through a suction-pipe *f*.

The discharge-pipe *g* from the pump leads 40 to an elevated receiving and equalizing chamber *h*, the interior of which is connected with the interior of the separator by an equalizing-pipe *i*. From the equalizing-chamber *h* a discharge-pipe *j* leads to a seal-pot *k*, from 45 the upper part of which leads a drain-pipe *m*.

The valve *n* in the steam-supply pipe *o* to the pump *e* is connected by suitable power-transmitting connections *p*² *q* *r* with a float *s* in the drip-chamber *d*. As shown, a lever *r*

has its fulcrum in the drip-chamber *d*, with 50 one arm inside of the chamber carrying the float *s* and the other arm outside of the chamber connected by a link *q* with a lever *p*², connected with the steam-valve *n*.

When the level of the liquids in the drip-chamber *d* is low, the steam-valve *n* is closed and the pump is inactive. Whenever the contents of the chamber *d* rise above the normal level, the float *s*, acting through the connections *p*² *q* *r*, will open the valve *n* and the 55 pump will operate to discharge the contents of the drip-chamber through the pipes *f* and *g* into the equalizing-chamber *h* until the normal low level is restored, when the steam-valve *n* will be closed and the pump will cease 60 to operate. The contents of the drip-chamber will therefore never be entirely discharged, and consequently there can be no escape of steam from the separator.

By arranging the pump *e* at a lower level 70 than the drip-chamber *d*, with the equalizing-chamber *h* at a higher level, it follows that as the same partial vacuum is maintained in the equalizing-chamber as exists in the separator and its drip-chamber the contents of 75 the drip-chamber will drain by gravity through the discharge-pipe *f* and pump *e* and will ascend in the pipe *g* to the level of the contents of the drip-chamber *d*. Consequently the pump will have only the work of 80 lifting the column of liquid from that level to the equalizing-tank *h*. While this arrangement of the pump *e* at a lower level than the contents of the chamber *d* is desirable, it is not essential and the pump may be placed at 85 a higher level.

The end of the discharge-pipe *j* from the equalizing-chamber *h* dips into the liquid seal in the pot *k*, and consequently the partial vacuum in the chamber *h* and in the separator is maintained.

As the vacuous condition maintained in the equalizing-chamber *h* will support a column proportional to the pressure within the separator, it is desirable in ordinary plants that 90 the length of the pipe *j* above the level in the seal-pot *k* should not be less than thirty-four feet. The contents of the chamber *h* may then

drain freely through the pipe *j* into the seal-pot *k* and the outflow will be discharged through the pipe *m*. Provided the proper lengths be maintained in the pipes *j* *g* with reference to the equalizing-chamber *h* and seal-pot *k*, it is immaterial what positions they occupy with reference to the separator.

A special advantage of my improvements is that they are entirely automatic and require no regulation or attention from the engine-driver.

With the separator operating under conditions of partial vacuum the oil is positively removed at all times without any loss of vacuum and it is not necessary to produce a greater partial vacuum in the pump *e* than exists in the separator.

What I claim as new, and desire to secure by Letters Patent, is as follows:

20 1. The combination with an oil-separator, of a pump connected with the drip-discharge thereof, a discharge-line from said pump, means to seal said discharge-line to air while permitting the escape of liquids, and means controlled by the level of the drips in the separator to control the operation of the pump.

25 2. The combination with an oil-separator, of a pump connected with the drip-discharge thereof, means controlled by the level of the drips in the separator to control the operations of the pump, a discharge-pipe from the pump, a receiving-chamber with which said discharge-pipe communicates, means to equalize the pressure in said receiving-chamber and

30 35 separator and a liquid-sealed discharge-pipe leading from said receiving-chamber.

3. The combination with an oil-separator, of a pump connected with the drip-discharge thereof, means controlled by the level of the

drips in the separator to control the operations of the pump, a liquid-sealed discharge-line leading from said pump, and means to equalize the pressures in said discharge-line and the separator.

4. The combination with an oil-separator, of a pump connected with the drip-discharge thereof, means controlled by the level of the drips in the separator to control the operations of the pump, a discharge-pipe from the pump, a receiving-chamber with which said discharge-pipe communicates, means to equalize the pressure in said receiving-chamber and separator, and a liquid-sealed discharge-pipe leading from said receiving-chamber the height of said discharge-pipe from the receiving-chamber being at least equal to the height of the column supported by the partial vacuum maintained in the separator.

5. The combination with an oil-separator, of a pump connected with the drip-discharge thereof and arranged at a level substantially below said drip-discharge, means controlled by the level of the drips in the separator to control the operations of the pump, a discharge-pipe from the pump, a receiving-chamber with which said discharge-pipe communicates located at an elevation above said pump, means to equalize the pressure in said receiving-chamber and separator, and a liquid-sealed discharge-pipe leading from said receiving-chamber.

In testimony of which invention I hereunto set my hand.

MILLARD P. OSBOURN.
